UNITED STATES PATENT OFFICE.

MILES McINTYRE, OF HEALDSBURG, CALIFORNIA.

WRENCH.

Application filed January 21, 1924. Serial No. 687,623.

To all whom it may concern:

Be it known that I, MILES McINTYRE, a citizen of the United States, and a resident of Healdsburg, county of Sonoma, State of

5 California, have invented a new and useful Wrench, of which the following is a specification.

The present invention relates to improvements in wrenches and has particular reference to a wrench designed to be used in the adjustment of the bands in a transmission arrangement used in a Ford car. To adjust the latter bands it is necessary to unscrew the cover of the transmission case and to 10 manipulate various nuts and rods which are hard to reach by the use of ordinary tools such as are commonly carried in automobile tool kits. It is proposed in the present invention to provide a combination wrench 15 made for the particular purpose of adjusting the bands referred to and to combine in one the various tools that might otherwise have to be used, so that the operator may perform the whole operation of adjusting 20 the bands with the one wrench, which is very inexpensive and simple. Further objects and advantages of my device will appear as the specification proceeds.

The preferred form of my invention is 25 illustrated in the accompanying drawing, in which Figure 1 shows a perspective view of the top portion of the Ford transmission case for which my wrench is made, Fig. 2 is a plan view of my wrench, and Fig. 3 is a 30 side view of the same.

While I have shown only the preferred form of my invention, I wish to have it understood that various changes or modifications may be made within the scope of the 35 claims hereto attached without departing from the spirit of the invention.

The transmission case 1 for which my wrench is made is substantially cylindrical in form and provided with an embossment 2 40 projecting from the cylinder and providing a flat face for the transmission cover 3, which latter is secured to the transmission case by means of screws 4. The transmission mechanism included in the case is the 45 so-called planetary system and includes three drums surrounded by three bands, 5, 6, and 7, the first one of which is the reverse speed band and the second one of which is the slow speed band, while the third is the 50 brake band. The bands, which are split, are provided with perforated lugs at their ends,

through which extend three shafts, 8, 9, and 11, commonly known as the reverse pedal shaft, the slow speed shaft, and the brake 60 pedal shaft. Each shaft has coiled thereon a spring 12, which latter has a tendency to open the bands when the means for contracting the same, as the various foot-pedals, are released.

To adjust the reverse speed band it is necessary to turn the nut 13, and to adjust the brake band the nut 14 must be turned. To adjust the slow speed band it is necessary to turn the shaft 9 which extends through the wall of the embossment previously referred 70 to and terminates in a flat portion 16 adapted to be manipulated by means of a wrench. The latter shaft is held in place by means of a lock-nut 17 adapted to be tightened 75 against the wall of the embossment.

To manipulate the nut 13 for adjusting the reverse speed band it is necessary to use a wrench of a particular form that may be introduced into the aperture of the embossment and with its outer end projecting outside of the embossment will allow at least a one-sixth of a revolution to be made so as to be able to take a new bite every time it is stopped due to its coming in contact with the edge 18 of the embossment. My wrench 80 19 consists of a strip of metal curved at one end in the plane of the strip as shown at 21 and formed at its end with a recess 22 adapted to receive a hexagonal nut.

The shank 23 of the wrench is disposed 85 substantially at right angles to the center line of the recess 22, and it should be particularly noted that while the other end of the wrench for the purposes hereinafter mentioned must be larger than that portion of the shank adjacent to the recess 22, and while the front edge 24 of the wrench runs straight from one end to the other of the same, the rear edge 26 instead of directly connecting the two ends of the wrench is indented as shown at 27, this indentation being just sufficient to allow a one-sixth of a turn to be made while engaging the nut 13 before the edge 18 of the transmission case 90 is touched.

The nut 14 is comparatively easy to manipulate and the same end of the wrench may be used for that purpose. Some difficulty arises in the turning of the slow speed adjusting screw 9. It will be realized 100 that the latter screw, which extends through the wall of the embossment, is disposed in 105 110

rather close proximity to the cylindrical portion of the transmission case, which renders the said screw and its lock-nut rather difficult of access. My wrench is formed at 5 its other end with a perforation 28 in which the lock nut 17 may be received, and is furthermore provided rearwardly of the perforation 28 with a second perforation 29 which fits on the end of the slow speed adjusting screw.

The particular arrangement of these two perforations is of importance in so far as the extreme perforation 28 is used for manipulating the nut 17 which latter is in the most 15 awkward position, while the perforation 29 which occupies a more unfavorable place on the wrench is used in connection with the more favorably situated end 16 of the slow speed adjusting screw.

20 To allow any turn of the wrench to be executed with ease, unhampered by the bulging out of the cylindrical portion of the transmission case, the extreme end of the wrench is turned out of the plane of the latter, preferably along the line 31 lying between the two perforations 28 and 29.

The wrench is furthermore reduced in thickness at its extreme end as shown at 32 so that it may be used as a screw-driver for 30 removing the screws 4.

The advantages of my wrench will be 35 readily understood from the foregoing description. To remove the cover of the transmission case, the wrench is used as a screw-driver by introducing the tapered portion 32 into the slots of the screws 4.

After the cover has been removed the nut 13 may be adjusted by utilizing the recessed 40 end of the wrench, which due to the form of the shank allows a one-sixth of a turn to be executed before the edge 18 is touched and so that a new bite may be readily obtained.

The nut 14 is comparatively easy to turn

by means of the same end of the wrench. 45 To adjust the slow speed adjusting screw 9 the nut 17 is loosened by using the extreme end of the wrench allowing the nut 17 to be received in the perforation 28. After the nut has been loosened, the end 16 50 of the slow-speed adjusting screw is introduced into the perforation 29 of the wrench and may be readily turned, due to the fact that the extreme end of the wrench is turned so as not to strike the bulging portion of the 55 transmission case.

It will be seen that in this manner any necessary adjustment may be readily carried out by the use of one single simple tool of 60 the character described.

I claim:

1. As an article of manufacture, a wrench comprising a flat strip of metal curved at one end in the plane of the strip and formed with an angular recess in said end, widened 65 at the other end and formed with a nut receiving perforation near said end and with a second perforation rearwardly of the first perforation, the front edge of the wrench being substantially straight and the back 70 edge being drawn in to allow the first mentioned recess to be used in connection with an existing mechanical arrangement.

2. As an article of manufacture, a wrench comprising a flat strip of metal curved at 75 one end in the plane of the strip and formed with an angular recess in said end, widened at the other end and formed with a nut receiving perforation near said end and with a second perforation rearwardly of the first 80 perforation, the latter end being bent out of the plane of the wrench between the two perforations and the front edge of the wrench being straight and the back edge drawn in to allow the wrench to perform 85 various functions in an existing mechanical arrangement.
